UNITED STATES PATENT OFFICE.

PERLEY D. HAM, OF GARFIELD, NEW JERSEY.

METALLIC CONTAINER.

1,111,576.

Specification of Letters Patent. Patented Sept. 22, 1914.

Application filed August 6, 1913. Serial No. 788,288.

To all whom it may concern:

Be it known that I, PERLEY D. HAM, a citizen of the United States, and a resident of Garfield, in the county of Bergen and State of New Jersey, have invented a new and Improved Metallic Container, of which the following is a full, clear, and exact description.

The invention relates to containers for containing shoe blacking, polishing preparations, paints, salves and other materials, and its object is to provide a new and improved metallic container having a tight-fitting cover and means for conveniently and quickly removing the cover from the body of the container and without danger of the operator soiling the hands or spilling the contents of the container.

In order to accomplish the desired result use is made of a cover fitting onto the body of the container, and prying means mounted on the said cover and engaging the said body to permit of prying the cover open.

A practical embodiment of the invention is represented in the accompanying drawings forming a part of this specification, in which similar characters of reference indicate corresponding parts in all the views.

Figure 1 is a perspective view of the metallic container with the cover closed and the prying means in inactive position; Fig. 2 is a plan view of the same; and Fig. 3 is a side elevation of the same with the parts in section.

The body A of the container is preferably made of sheet metal of a suitable size and depth and terminating at its upper edge in an outwardly-bent annular bead A'. The cover B for closing the body A is provided with an upwardly-extending flange B' fitting into the upper open end of the body A, and the said flange B' is provided at its upper edge with an outwardly-extending annular bead B² adapted to rest on top of the bead A' to limit the downward movement of the cover B in the open end of the body A. The flange B' of the cover B fits very snugly into the upper open end of the body A and in order to permit of conveniently removing the cover B from the said body A, use is made of prying means arranged as follows:

A bail C is provided near its ends with outwardly-extending offsets C' terminating in trunnions C² journaled in the flange B' of the cover B at diametrically opposite points, and the outer ends of the said trunnions C² terminate in lengthwise-extending prying

arms C³ extending in spaces B³ formed by flattening the corresponding portions of the bead B² of the cover B. When the bail C is in folded position, that is, extends within the upper portion of the cover B then the prying arms C³ lie flat on the bead A', and when it is desired to pry the cover B open it is only necessary to swing the bail C upward so that the prying arms C³ in bearing on the bead A' lift the cover B out of the body A of the metallic container. When it is desired to replace the cover B the bail C is swung back into folded position and then the cover B is pressed down in the open top end of the body A.

In order to provide as much room as possible within the container A, the middle portion B⁴ of the cover B is bent upwardly to provide an annular space B⁵ into which the bail C is folded on swinging the bail downward into folded position. By providing the offsets C' the major portion of the bail C lies in close proximity to the exterior wall of the struck-up central portion B⁴ so as to provide sufficient room in the space B⁵ for the insertion of a finger or a tool with which to swing the bail C into open position whenever it is desired to pry the cover B open, as previously explained.

Although two prying arms C³ are shown, it is evident that one prying arm on one of the trunnions is sufficient to pry the cover B open when swinging the bail C upwardly, as previously explained.

It will be noticed that the bail C when swung into open position serves to conveniently carry the cover B about and to manipulate the same while lifting the pried open cover from the body A or replacing it thereon.

It will further be noticed that the bail C forms a permanent part of the cover B, and when the container is closed and the bail C is in folded position then it forms no undesirable projection, and a series of containers can be readily stacked without the slightest interference by the bails C.

Having thus described my invention, I claim as new and desire to secure by Letters Patent:

1. In a metallic container, the combination of a body having an external bead at the upper edge, a cover fitting into the upper end of the said body and having an external bead opposite the said body bead, the said cover bead having flattened portions at

diametrically opposite points to provide spaces between the beads at the time the cover is in closed position on the said body, the top of the said cover being provided 5 with an annular depression adjacent the said cover bead; and a bail of approximately segmental shape normally extending in the said depression, the bail having trunnions journaled in the sides of the cover at the 10 flattened bead portions, the trunnions terminating in prying arms extending in the said bead space and overlying the body bead to pry the cover open on imparting an upward swinging motion to the said bail.

15 2. A metallic container, comprising a body provided with an external bead at the upper edge, a cover fitting into the upper end of the said body and provided with an external bead adapted to engage the bead on the said 20 body to limit the inward movement of the cover on the body when placing the cover in position on the body, diametrically opposite portions of the said cover bead being flattened to provide spaces above the body 25 bead at the time the cover is in closed position, the top of the said cover being provided with an annular depression adjacent the said cover bead; and a bail of approximately 30 segmental shape normally extending in the said depression, the bail having trunnions journaled in the sides of the cover at the said flattened bead portions, the trunnions terminating in prying arms extending in the said bead spaces and overlying the 35 bead of the body to pry the cover open on

imparting an upward swinging motion to the said bail.

3. A metallic container, comprising a body provided with an external bead at the upper edge, a cover fitting into the upper end of the said body and provided with an external bead adapted to engage the bead on the said body to limit the inward movement of the cover on the body when placing the cover in position on the body, diametrically opposite portions of the said cover bead being flattened to provide spaces above the body bead at the time the cover is in closed position, the said cover being provided with an annular space adjacent the cover bead 40 and below the top of the cover; and a segmental bail having trunnions journaled in the sides of the cover at the said flattened bead portions, the trunnions terminating in prying arms extending 45 in the said bead spaces and overlying the bead of the body to pry the cover open on imparting an upward swinging motion to the said bail, the said bail being provided with offsets adjacent the trunnions, the said 50 bail and its offsets normally extending in a horizontal plane and within the said annular space.

In testimony whereof I have signed my name to this specification in the presence of 65 two subscribing witnesses.

PERLEY D. HAM.
